UNITED STATES PATENT OFFICE.

AUGUST C. STOLL, OF ANN ARBOR, MICHIGAN.

SPIGOT.

1,381,598.

Specification of Letters Patent. Patented June 14, 1921.

Application filed February 17, 1920. Serial No. 359,390.

To all whom it may concern:

Be it known that I, AUGUST C. STOLL, a citizen of the United States, residing at Ann Arbor, in the county of Washtenaw, State 5 of Michigan, have invented certain new and useful Improvements in Spigots; and I do hereby declare the following to be a full, clear, and exact description of the invention, such as will enable others skilled in the art 10 to which it appertains to make and use the same.

This invention relates to new and useful improvements in spigots and particularly to spigots used in connection with barrels, 15 tanks, or the like receptacles containing fluids.

One object of the present invention is to provide a novel and improved spigot which will automatically close whereby leakage 20 and loss of liquid, due to the spigot being carelessly left open, is obviated.

Another object is to provide a novel and improved spigot of this character wherein the flow of liquid therethrough is controlled 25 at two points, thus more effectively sealing the liquid from leakage.

Other objects and advantages will be apparent from the following description when taken in connection with the accompanying 30 drawing.

In the drawing:

Figure 1 is a side elevation of a spigot made in accordance with the invention.

Fig. 2 is a vertical longitudinal central 35 sectional view through the spigot.

Fig. 3 is a vertical transverse central sectional view through the spigot.

Fig. 4 is a vertical longitudinal sectional view taken on a line at one side of the median line of the spigot to show one of the side cavities and the closing spring therein, 40 together with the plug carried lug engaging therewith.

Referring particularly to the accompanying drawing, 10 represents the barrel or outer casing of the spigot, one end being tapered and externally threaded at 11 for engagement in the bung hole of a barrel, tank, or other receptacle containing the fluid, 45 while the other end is externally threaded at 12 for the engagement thereon of the centrally apertured cap 13. The tapered end of the casing or barrel of the spigot is closed by the wall 14, in which is formed an opening 15, while the other end is open to receive therein the inner cylinder or plug of

the spigot, said plug being shown at 16. The inner end of the cylinder is closed by a wall 17 in which is formed an opening 18 for registry with the opening 15, when the 60 spigot is in open position. The cylinder is hollow and has its outer end closed by a thicker wall 19 into which is secured the stem of the handle 20, said handle being engaged through the central aperture of the 65 cap 13. In one side of the casing there is formed the spout 21 with which an opening 22, formed in the side of the cylinder, is adapted to register when the openings 15 and 18 are in register, and through which 70 the liquid passes from the receptacle.

Formed longitudinally in the inner face of the casing, at diametrically opposite points, are the channels or recesses 23, in which are movable the longitudinal ribs 24 75 formed on diametrically opposite sides of the cylinder within the casing. In each of the recesses is disposed a longitudinally extending bowed spring 25, the ends of which rest against one wall of the recess while the 80 intermediate portion of the spring is engaged by the rib 24.

When the handle is turned in one direction, the cylinder will be rotated to register the openings 15 and 18, and register the 85 opening 22 with the spout 21. In this position the ribs of the cylinder will flatten out the springs, thus placing them under tension so that when the handle is released, the 90 springs will resume their normal conditions, at the same time rotating the cylinder back into its original position, with the result that the openings 15 and 18, and the opening 22 and spout 21, will be moved out of register, and the flow of liquid stopped. 95

It will be noted that the liquid is controlled at two points, one at the receptacle end of the spigot, and the other at the spout.

What is claimed is:

1. A spigot including a casing having an inlet and an outlet, a turning plug in the casing and having an inlet and an outlet for simultaneous register with the inlet and outlet of the casing, and means between the turning plug and the casing for rotating the 100 turning plug to yieldably hold the turning plug in such position that the inlets and outlets remain out of register. 105

2. A spigot including a casing having an inlet and an outlet, a hollow member rotatable within the casing and having an inlet 110 and an outlet for register with the corre-

sponding openings of the casing at times, the inner walls of the casing having recesses, the hollow member having longitudinal ribs, and resilient members in the recesses and engageable between the walls of the recesses and the ribs to maintain the hollow member in such position that the inlets and outlets are out of register.

3. A spigot including a casing having an inlet opening in one end and an outlet opening adjacent the other end, a hollow cylinder rotatable within the casing and having an inlet arranged to register, at times, with

the first inlet; and an outlet arranged to register, at times, with the first outlet, the inner walls of the casing having longitudinally extending recesses, the opposite sides of the cylinder having longitudinal ribs movable in the recesses, and longitudinally extending bowed springs in the recesses. 15 20

In testimony whereof I affix my signature in the presence of two witnesses.

AUGUST C. STOLL.
